TELEPHONE SWITCHBOARD HOUSING

Robert E. Bearse, New York, N.Y., assignor to Western
Electric Company, Incorporated, New York, N.Y., a
corporation of New York

Filed Dec. 16, 1968, Ser. No. 14,985

Term of patent 14 years

Int. Cl. D14—03

U.S. Cl. D26—14

FIG. 2

FIG. 3

FIG. 1 is a perspective front, top and left side view of a telephone switchboard housing showing my new design;

FIG. 2 is a left side elevational view thereof; and

FIG. 3 is a right side elevational view thereof.

The broken lines are shown for illustrative purposes only.

I claim:

The ornamental design for a telephone switchboard housing, substantially as shown and described.
